UNITED STATES PATENT OFFICE

150,828

DESIGN FOR A CROCHETED DOILY OR THE LIKE

Mildred R. Craig, Erwin, W. Va.

Application May 8, 1947, Serial No. 138,922

Term of patent 3½ years

(Cl. D3—9)

To all whom it may concern:

Be it known that I, Mildred R. Craig, a citizen of the United States and a resident of Erwin, in the county of Preston and State of West Virginia, have invented a new, original, and ornamental Design for a Crocheted Doily or the like, of which the following is a specification, reference being had to the accompanying drawing, forming a part thereof, wherein

Fig. 1 is a plan view of a crocheted doily or the like showing the major portion of my new design; and

Fig. 1A is a similar view showing the balance thereof.

The two views joined together at the lines a—a thereof show the complete crocheted doily or the like.

I claim:

The ornamental design for a crocheted doily or the like, as shown and described.

MILDRED R. CRAIG.
